UNITED STATES PATENT OFFICE.

RODOLPH F. MORSE, OF PROVIDENCE, RHODE ISLAND.

GRATE-BAR.

1,155,674.

Specification of Letters Patent.

Patented Oct. 5, 1915.

Application filed July 20, 1915. Serial No. 40,850.

To all whom it may concern:

Be it known that I, RODOLPH F. MORSE, a citizen of the United States, residing at Providence, in the county of Providence and State of Rhode Island, have invented certain new and useful Improvements in Grate-Bars, of which the following is a specification.

My invention relates to improvements in cast-metal grate-bars for furnaces, and it consists in the novel construction of the bar itself, which constitutes a unit member of the grate.

In the accompanying drawings, illustrating my improvement, Figure 1 is a top plan view of the grate-bar or unit member; Fig. 2 is a side view, in enlarged scale, showing a plurality of the units mounted for rocking or shaking action; Fig. 3 is an enlarged transverse sectional view, taken on line 3—3 of Fig. 1; and Fig. 4 is an end view, showing a detail.

It is to be understood that the members or elements comprising my improved grate-bar A are cast from a pattern and constitute a single casting or unit.

My invention resides essentially in providing the grate-bar unit A with a plurality of uniformly spaced parallel transverse members or cross-bars n, having the portion m of the latter, intermediate the longitudinal side ties b b, bent laterally in vertical planes to form curved parallel air spaces s, and having the upper or top face t of the cross-bar members n crowning or curved longitudinally from one end to the other; each of said upper faces of the members n is provided with a continuous score or groove g formed therein for the retention of ashes. It may be added that the said groove conforms to the vertical and lateral curvatures of the members n, as represented most clearly in Figs. 1 and 3.

The grate-bar is provided with end members a a, each end having a short longitudinally extending trunnion or journal a¹ disposed centrally near its upper edge. One of the said ends has a downward extension a² adapted to connect with a horizontally movable rod d², jointed to a link d⁴, in turn jointed to a vertical lever d pivoted at e¹ to a bracket e secured to a stationary front member f of the furnace. Upon oscillating the handle bar l the thus connected and supported grate bar units A, when mounted in a furnace, are caused to rock simultaneously

in a well known way; an excess movement permits the fire coals and ash on the grate to be dumped. Stationary side bars B, having spaced recesses t¹ formed in the upper edge to receive the trunnions a¹, in connection with stationary front and back members, f and s¹, respectively, may be employed to support the several grate-bars constituting the net grate surface or area.

By means of my improved grate-bar unit construction the cross-bar members n thereof are adapted to more successfully withstand the forces of expansion and contraction without injury to the grate. Another advantage resulting from the said curved form is that air passing upward through the air passages s is more evenly distributed through the fire on the grate, thus increasing the efficiency of the coal by its more perfect combustion. At the same time the grooves g serve to retain fine ash lodged therein, thereby preventing the cross-bar members n from becoming overheated and warped, thus prolonging the life and usefulness of the grate and reducing the cost incident to renewal and repair.

I claim:

1. A grate-bar having the following elements or members arranged and cast in one piece and forming a unitary grate-bar, said grate-bar consisting of the two ends, each end having a trunnion or journal, one of the ends being also provided with a downward extension arranged to connect with manually controlled means for tilting or rocking a plurality of the grate-bars, a pair of parallel longitudinally extending main tie bars connecting said ends, a plurality of parallel transverse cross-bar members spaced longitudinally on and uniting the said tie-bars, the upper face or edge of each transverse cross-bar being convex and provided with a longitudinally extending groove adapted to retain ashes, and having the portion of the cross-bar members intermediate the main tie-bars curved laterally or sidewise in a horizontal plane to produce between each pair of contiguous cross-bars a correspondingly curved vertical opening for the passage of air.

2. The combination with relatively stationary side members adapted to support a fire-grate, of a plurality of grate-bar units movably mounted on the said side members, each of the said grate-bar units cast in one piece and consisting of a plurality of par-

allel longitudinal side ties or bars disposed in a horizontal plane, oppositely arranged transverse end members connecting said side-ties, a plurality of spaced parallel transverse cross-bar members extending across and uniting the said side-ties, said transverse cross-bar members being curved laterally in a horizontal plane, correspondingly curved open passages formed between the adjacent sides of the respective transverse cross-bar members, the upper face of the said transverse cross-bars being convex and each provided with a longitudinal groove adapted to retain ashes, and manually controlled means connected with the grate-bar units for tilting the latter in unison.

3. A cast metal grate-bar unit for furnaces, comprising a pair of laterally separated longitudinal main ties, means connect-

ing the ends of the ties together, and a plurality of cross bars spaced longitudinally on the main ties connecting the latter transversely to form an unobstructed passage for air between the adjacent sides of each pair of cross-bars and the inner sides of said longitudinal main ties, said cross-bar members being curved laterally in a horizontal plane and having their upper faces convex and provided with longitudinal grooves conforming to the lateral and vertical contours of the cross-bar members.

In testimony whereof I have affixed my signature in presence of two witnesses.

RODOLPH F. MORSE.
